[57] CLAIM

The design for the video cassette, as shown and described.

DESCRIPTION

FIG. 1 is a top plan view of a video cassette showing our new design;

FIG. 2 is a bottom plan view thereof;

FIG. 3 is a front elevational view thereof;

FIG. 4 is a rear elevational view thereof;

FIG. 5 is a right side elevational view thereof, the left side being a mirror image; and,

FIG. 6 is a right side elevational view of a second embodiment of the video cassette illustrated in FIG. 1, the left side being a mirror image.

The top, bottom, front and rear of the second embodiment are the same as the corresponding views of the first embodiment.

FIG. 1

FIG. 2

FIG. 3

FIG. 4

FIG. 5

FIG. 6
